Nelson McDonald

UNITED STATES PATENT OFFICE.

WARREN G. CHESLEY, OF PHILADELPHIA, PENNSYLVANIA, ASSIGNOR, BY MESNE ASSIGNMENTS, TO UNITED SHOE MACHINERY CORPORATION, OF PATERSON, NEW JERSEY, A CORPORATION OF NEW JERSEY.

GRIPPER MECHANISM FOR LASTING-MACHINES.

1,282,191.

Specification of Letters Patent.

Patented Oct. 22, 1918.

Application filed March 19, 1917. Serial No. 155,892.

To all whom it may concern:

Be it known that I, WARREN G. CHESLEY, a citizen of the United States, residing at Philadelphia, in the county of Philadelphia and State of Pennsylvania, have invented 5 certain Improvements in Gripper Mechanisms for Lasting-Machines, of which the following description, in connection with the accompanying drawings, is a specification, 10 like reference characters on the drawings indicating like parts in the several figures.

This invention relates to gripper mechanisms and particularly to power operated gripper mechanisms of lasting machines. It 15 is important, in order to maintain the efficiency of power lasting machine grippers in which the gripper closing movements are effected by cams having a constant throw, to provide an adjustment for accurately controlling the extent of normal closure of the jaws, and for taking up wear of the parts. It is the object of this invention to provide 20 an improved adjusting means and particularly one possessing accuracy and firmness of adjustment in a superior degree. One feature of the invention consists in the combination with a bar and a jaw fixed on the bar, of a jaw movably connected with the bar, a cam on the bar operative to assist in 25 the closing of the movable jaw, and a wedge adjustment for the cam.

This and other features of the invention, including certain combinations of parts and more important details of construction will 30 now be described, with the aid of the accompanying drawings and will then be pointed out in the claims.

Figure 1 is a side view partly in section, of a gripper of the type shown in Ladd and 35 Stiggins, United States Letters Patent No. 1,005,234, and equipped with this invention.

Fig. 2 is a perspective view of parts of the adjusting mechanism.

The gripper in which the invention is 40 herein shown as embodied for illustrative purposes comprises a bar 1 having a ball head 2 from which it is suspended and having a guideway for the push rod 3 that is connected by a link 4 with the upper end of 45 swinging jaw 5. The jaw 5 co-operates with a jaw 6 that is rigidly secured to the lower part of bar 1 to which jaw 5 is also connected by a swinging link 7. It is a characteristic 50 of this gripper that the jaw 5 is made to

reach out relatively to jaw 6 to embrace the stock during the first part of its closing movement and then to swing sharply in toward the jaw 6 during the final portion of its closing movement. This characteristic motion is produced by the co-operation of 60 link 7 and a cam 8 with which the heel on the upper end of jaw 5 is held in contact by a spring, as shown in Fig. 1. As thus far described the gripper is substantially like the disclosure in said patent. 65

The cam 8 is partially received in a recess in the adjacent wall of the bar 1 in which it is supported by a stem 12 the outer end of which is threaded and carries a nut 13 by which the cam can be clamped rigidly 70 against the rear wall of its recess in bar 1. Said wall is, in accordance with this invention, further recessed to receive a wedge 15, see Fig. 2, shown as split to embrace the stem 12 and bear against the rear face of the cam 75 8 adjacent to the stem. The bar 1 carries a set screw 16 in position to engage the head of wedge 15 and force it in the direction to project the cam outwardly and move the heel end of jaw 5 outwardly and its gripping 80 end inwardly toward jaw 6. This gripper jaw adjustment by wedge 15 can be effected when nut 13 has been loosened. The nut 13 and set screw 16 fix the adjusting means 15 absolutely rigid in bar 1 and there is no 85 chance of its working loose during use of the machine. When the gripping faces of the jaws have worn, or wear anywhere in the connections between jaw 5 and its closing cam, not shown, has lessened the closeness of 90 approach of the jaws, the cam 8 can be set forward with accuracy and secured rigidly by the described manipulation of the nut, setscrew and wedge and the result can be absolutely relied upon. 95

Having described the invention, what I claim as new and desire to secure by United States Letters Patent is:

1. In a gripper mechanism, the combination with a jaw and a co-operating jaw movable to effect gripping, of jaw moving means comprising a cam, a support for the cam, a stem extending from the cam through the support, a nut co-operating with the stem and support to clamp the cam, a wedge adjustable between the cam and support, and means for holding the wedge in adjusted position. 100 105

2. In a gripper mechanism, the combination with a jaw and a coöperating jaw movable to effect gripping, of jaw moving means comprising a cam, a support for the cam, a wedge adjustable between the support and cam to control the projection of the cam, and means for relatively fixing the wedge and cam in adjusted relation.
3. In a gripper mechanism for lasting machines, the combination with a bar and a jaw fixed on the bar, of a jaw movably connected with the bar, a cam on the bar operative to assist in the closing of the movable jaw, and a wedge for adjusting the cam.
4. In a gripper mechanism for lasting machines, the combination with a bar and a jaw fixed on the bar, of a jaw movably connected with the bar, a cam on the bar operative to assist in the closing of the movable jaw, said cam having a stem projecting rearwardly through the bar, a clamping nut on the stem and a wedge adjustable in the bar and against which the cam is clamped by the stem and nut.
5. In a gripper mechanism for lasting machines, the combination with a bar and a

jaw fixed on the bar, of a jaw movably connected with the bar, a cam on the bar operative to assist in the closing of the movable jaw, said cam having a stem projecting rearwardly through the bar, a wedge arranged between the cam and bar and forked to engage the cam upon opposite sides of the stem, and means for securing the wedge and the stem for holding the cam in different adjusted positions on the bar.

6. In a gripper mechanism for lasting machines, the combination with a bar and a jaw fixed on the bar, of a second jaw, a link connecting the second jaw to the bar, a push rod for moving the jaw toward the fixed jaw in a path controlled in part by the link, a cam carried by the bar and in sliding relation to which the upper end of the movable jaw travels, means for securing the cam to the bar and a wedge adjustable to cause the cam to project more or less from the bar into the path of the jaw.

In testimony whereof I have signed my name to this specification.

WARREN G. CHESLEY.
